STANDARD CAR TRUCK COMPANY, OF CHICAGO, ILLINOIS, A CORPORATION
OF NEW JERSEY.

SIDE BEARING FOR CARS.

1,177,591.

Specification of Letters Patent.

Patented Apr. 4, 1916.

Application filed December 18, 1915. Serial No. 67,568.

To all whom it may concern:

Be it known that we, LEE W. BARBER and EDWIN W. WEBB, citizens of the United States, residing at Chicago, in the county of Cook and State of Illinois, have invented certain new and useful Improvements in Side Bearings for Cars; and we do hereby declare the following to be a full, clear, and exact description of the invention, such as will enable others skilled in the art to which it appertains to make and use the same.

Our invention has for its object to provide an improved side bearing for railway cars, and to such ends, generally stated, the invention consists of the novel devices and combinations of devices hereinafter described and defined in the claims.

In the accompanying drawings which illustrate the invention, like characters indicate like parts throughout the several views.

Referring to the drawings: Figure 1 is a plan view of the improved side bearing; Fig. 2 is a side elevation thereof; Fig. 3 is a section taken on the line $x^3 x^3$ of Fig. 1; and Fig. 4 is a section taken on the line $x^4 x^4$ of Fig. 1.

The housing is made up of two sections, to-wit, an upper and a lower section, and both of these sections are preferably castings, although the top member, especially, might be a pressed steel member. The lower half 1 of the housing has a flanged base adapted to be riveted, bolted, or otherwise rigidly secured to the ends of a truck bolster. The body of the said lower member is a box-like structure cast integral with the base and suitably ribbed, and in its side walls, it is formed with approximately semi-cylindrical recesses adapted to receive the ends of pins 2 on the intermediate portions of which rollers 3 are journaled. The said seats for the ends of the pins 2, above the horizontal plane of the axes of the pins, flare upward slightly, so that they are adapted to be drawn from the sand in the process of casting. The base member 1, just below the rollers 3, is cut through at 4, so that sand and dirt may work downward out of the box, it being assumed, of course, that the bolster will have some provision, such as a passage to permit precipitation of the dirt.

The upper portion 5 of the housing is an approximately H-shaped structure which fits upon the top of the box-like body portion of the lower member 1 with its bifurcated end portions embracing the upper portions of the rollers 3, and resting on or immediately over the ends of the pins 2, being, as shown, provided with seats for engagement with the pins, which seats are preferably a little less than one-half cylindrical. At the outer extremities of its seats, the inner and outer walls of the said upper member 5 extend below and outward of the ends of the coöperating pins 2 to afford lips 6 that positively hold the said pins against endwise displacement. It therefore, of course, follows that the said pins must be inserted in position before the upper member 5 is secured to the lower member 2. As a simple and efficient means for rigidly connecting the said members 1 and 5, they are provided at the central portions of their inner and outer sides with engaging horizontally projecting flanges 7 rigidly united by rivets 8. Thus it will be seen that when the upper section is applied to the lower section of the housing, the pins are positively held in working position.

As a highly important feature of this invention, the top of the housing is formed with a smooth flat upper bearing surface 9 that is normally slightly below the upper surface of the rollers 3. The roller engaging bearing surface carried by the body bolster of the car will normally be engaged with the upper surfaces of the rollers 3, but it is adapted to drop down into engagement with the said flat bearing surface 9 whenever the rollers are broken or lost out in any way, or for any reason, have been removed. It is, therefore, important that the said bearing surface 9 stands very close to the upper surface of the rollers so that the play between the upper and lower side bearing members on the truck bolster and body bolster, will not vary much under the different conditions above noted. The bearing surface 9 is therefore in the nature of an auxiliary or reserve bearing element which becomes useful in emergency and prevents the side bearing from becoming disabled by breaking either of the pins or rollers. Also, in case of extreme wear of

the pins or rollers or the pin engaging seats, the said bearing surface 9 will be brought into action.

What we claim is:

1. A side bearing for cars comprising a housing made up of rigidly connected upper and lower members, a pin seated in the lower member with freedom for lateral and endwise displacement and held in position by the upper member against lateral and endwise displacement, and a roller on said pin.
2. A side bearing for cars comprising a housing made up of rigidly connected upper and lower members, said lower member having open topped pin seats extending completely through its side walls, pins having their ends seated in said open seats with freedom for lateral and endwise displacement, the said upper member having flanges that overlap the ends of said pins.

Copies of this patent may be obtained for five cents each, by addressing the "Commissioner of Patents, Washington, D. C."

and hold the same against endwise displacement, and rollers on said pins.

3. A side bearing for cars comprising a housing made up of upper and lower members, said upper member having a horizontal top bearing surface, a pair of rollers journaled in said housing with their upper surfaces at the same altitude slightly above said top bearing surface, said upper and lower members having horizontal flanges located between said rollers and below said top bearing surface, and rivets rigidly connecting said horizontal flanges.

In testimony whereof we affix our signatures in presence of two witnesses.

LEE W. BARBER.
EDWIN W. WEBB.
